CLAIM

The ornamental design for the condiment mill, as shown and described.

DESCRIPTION

FIG. 1 is a lower perspective view of the condiment mill showing my new design.

FIG. 2 is a front view thereof;

FIG. 3 is a back view thereof;

FIG. 4 is a side elevation view thereof;

FIG. 5 is an opposite side elevation view thereof;

FIG. 6 is a top plan view thereof; and,

FIG. 7 is a bottom plan view thereof.

The condiment mill is a kitchen tool that may be used for, among other things, grinding peppercorns or other spices.
